UNITED STATES PATENT OFFICE

2,112,018

DEVICE FOR ELIMINATING NOXIOUS
SUBSTANCES CONTAINED IN TOBAC-
CO SMOKE

Louis Georges Gautron, Geneva, Switzerland

Application October 4, 1934, Serial No. 746,854
In Switzerland October 15, 1933

1 Claim. (Cl. 131—12)

This invention relates to improvements in devices for eliminating noxious substances contained in tobacco smoke.

The accompanying drawing illustrates examples of construction of the invention.

Figure 1 is a vertical sectional view of a tobacco pipe embodying the present invention.

Fig. 2 is an elevational view of one of the cap-shaped members of the present invention with 10 the slit closed.

Fig. 3 is a view similar to Fig. 2 with the slit open.

Fig. 4 is an end view of the cap-shaped member.

As shown in the drawing, the pipe comprises a 15 bowl portion 6, a mouthpiece 7, and a connecting stem 5.

The bowl of the pipe is integral with a tube 6', connected to draw-tube or mouthpiece 7 for the smoke by means of tube or stem 5. A union 13 20 screwed into the mouthpiece 7 is forced into the tube 5 and a union 12 similarly connects the tubes 5 and 6'.

The stem portion of the bowl is provided with a chamber in which is mounted a smoke-treating unit. This unit comprises upper and lower tubular members 16 and 17, respectively, joined together as illustrated. The lower member 17 has a recessed portion 18 which is placed in register with the smoke duct 19 of the bowl. A nozzle 14 25 projects upwardly from the recessed portion of member 17 into the chamber 10 of the upper member 16 and has a rubber cap-shaped member 1 fitted thereon. The lower portion of member 17 30 serves as a receptacle 9 for saliva and is provided with a drain plug 11.

A cage-like member is carried by the upper end of member 16 for receiving and retaining a washer 4 filled with spongy material 3. Stem 5 has a tube 15 provided with a screw-threaded base 40 mounted thereon in axial alignment with the smoke duct thereof. This tube serves as a nozzle for conducting smoke into a chamber formed in the mouthpiece stem 7. A rubber cap-shaped member 2 is fitted on the end of tube 15.

Washer 8, filled with spongy material, surrounds tube 15 and is adapted to absorb the products of condensation and the saliva.

Cap-shaped members 1 and 2 are provided

with narrow slits 1' and 2' on their extremities. These slits permit smoke to pass in one direction, but prevent the flow of matter in the opposite direction.

The smoke is compelled to pass to the interior 5 of the cowls or cap-shaped members 1 and 2 and the flexible edges of the slits 1' and 2' which always tend to come into contact are parted only through the drawing of the smoke. The matters suspended in the latter are held back by the flexible edges of the slits, and if by condensation or any other cause, an efflux of matters outside the cowls is produced, it falls into the reservoir 9.

The pipe can be easily mounted and dismounted and its inner members cleaned or replaced by 15 others.

The outlet vent of the cowls instead of comprising one or more slits may be a very small hole of circular or other section, provided that it has at least one flexible edge which, continually tending to close the vent, is parted only by the exhaustion of the smoke.

What I claim as my invention and desire to secure by Letters Patent of the United States is:—

In a tobacco smoking device of the character described, a smoke conducting stem provided with upper and lower axially spaced chambers connected by a smoke duct, said lower chamber being divided into a lower liquid receiving reservoir, an intermediate smoke receiving compartment, and an upper filter compartment, the longitudinal axes of said compartments and reservoir being coincident with each other and with the longitudinal axis of said stem, a nozzle-like member 25 for introducing smoke into the smoke receiving compartment of the lower chamber, a rubber cap-shaped member fitted on said nozzle-like member, a nozzle-like fitting extending into the upper chamber for introducing smoke, passing through said duct from the lower chamber, into the upper 30 chamber, and a rubber cap-shaped member fitted onto said fitting, both of said rubber cap-shaped members having a small smoke filtering chordal slit formed in the closed end thereof, said slits being normally closed and adapted to permit the 40 passage of smoke therethrough.

LOUIS GEORGES GAUTRON.
